AMPLIFIER CIRCUITS

Application filed May 14, 1925. Serial No. 30,281.

This invention relates to amplifier circuits, and more particularly to amplifier circuits employing one or more electron discharge devices.

5 Oscillation or objectionable regenerative effects will occur in amplifier circuits if no means be employed to control the same, due to the electrostatic or electromagnetic coupling between the output and input circuits of the electron discharge amplifier or amplifiers. It has heretofore been proposed to prevent oscillation of an electron discharge amplifier by balancing out the effect of the electrostatic coupling between the plate and grid circuits, internally or externally of the tube, or by greatly reducing the coupling in the radio frequency transformer. If the effect of the electrostatic coupling is neutralized, it has been found necessary to over-neutralize at the lower frequencies in order to secure sufficient neutralization to prevent oscillation at the higher frequencies. Thus the sensitivity is greatly reduced at the lower frequencies. If oscillation or regenerative 25 effects are prevented by embodying a loose coupling, amplification is greatly reduced at the lower frequencies. Moreover, methods heretofore employed for controlling the radio frequency amplification, that is for preventing oscillation, have been such that the tone quality of the received signals on distant reception is inferior, due to the trimming of the side bands, etc., as is well understood in the art, and amplification over 30 part of the broadcast frequency range is greatly reduced.

An object of the present invention is to provide an amplifier circuit with novel means for overcoming the above defects.

40 Another object of the invention is to provide means for preventing cascaded audions from oscillating and at the same time secure a maximum of amplification over a wave length band.

45 Broadly stated, the invention consists in providing coupled circuits, one or more of which are resonant to the frequencies to be received, but which are so arranged that the voltages and currents in a succeeding stage 50 will be neither in phase nor 180° out of

phase with that in the preceding, but will be at some intermediate phase relation whereby it is possible to produce a greater amplification per stage before the point of oscillation is reached, and this without effecting the 55 broadness of tuning whereby equal amplifications of the side bands along with the carrier wave is secured with greatly improved quality of reproduction.

Two forms of the inventive idea are shown 60 in the accompanying drawings, which drawings, however, are for the purpose of illustration only and are not to be taken as a definition of the limits of the invention, reference being had to the appended claims for this 65 purpose.

In the drawings,

Fig. 1 shows diagrammatically two thermionic amplifiers connected in cascade in accordance with the present invention;

70 Fig. 2 is a diagrammatic view illustrating a second manner in which audions may be operatively associated in accordance with the present invention; and

Figs. 3 and 4 are vector diagrams illustrating the results that are secured by the circuit arrangement of the present invention.

Referring to the drawings, wherein like reference characters refer to like parts throughout the several views, and particularly to Fig. 1, the present invention is shown embodied in a circuit which includes the input terminals 1 and 2, of an electron discharge device 3, that are connected in any desired manner to a suitable current 80 source (not shown). Across the output terminals 2 and 4 of the audion discharge device 3 are connected, in the usual manner, the primary 5 of a radio frequency transformer 6, and the usual battery 7 for supplying the necessary voltage to the output terminal or plate 4. Inductively associated with the primary winding 5 is the secondary winding 8 of the radio frequency transformer, which secondary winding is preferably 90 tuned to the desired frequency in a well known manner by means of a variable condenser 9 in shunt thereto. The coupling between windings 5 and 8 may be closer than that usually employed in the well known 100

neutrodyne circuits, and preferably the primary is associated with the secondary in such a manner that the former is more closely coupled to one portion of the secondary than 5 to the remainder of the same.

In order to employ a close coupling between the windings of the transformer 6 and at the same time to avoid objectionable regenerative effects, or oscillation of the 10 electron discharge device 3, means are associated with the secondary winding 8 which constitute a load controllable in phase and amount whereby it is possible to maintain a coupling between the windings which, at 15 frequencies in the broadcast range, will give large amplification without regenerative distortion. In the form shown, this means is constituted by a condenser 10 in series with a resistance 11, said condenser and resistance 20 being shunted across a part of the secondary winding 8, as indicated at the points 12 and 13 on the latter. If desired, the connection 13 may be made at a suitable point 14 on a lead 15 connecting the secondary winding 8 25 and the tuning condenser 9, or the connection 13 may be made at a suitable point 16 in the tuned circuit 9, 8, 15 as indicated in dotted lines. The input terminals 17 and 18 of a second electron discharge device or 30 vacuum tube 19 may be connected in the usual manner to the secondary winding 8 and tuning condenser 9, or the same may be connected to any other desired circuit arrangement.

35 *Operation.*—If a signal voltage is applied to the input terminals 1 and 2 of the electron discharge device 3 by means of some suitable pick-up, such as a tuned loop or an antenna and ground, and any common type 40 tuner (not shown), said voltage is enlarged and reproduced between the output terminals 2 and 4 in a manner well understood in the art. This enlarged voltage or output will differ from the input voltage in a manner 45 which depends on the difference between the load in the output circuit and a pure resistance, and upon the non-linear characteristic of the plate current-grid voltage curve over the range used. In other words, as 50 the dynamic characteristic of the electron discharge device deviates from a straight line to a loop form, distortion is present. The flow of the alternating current through the primary winding 5 of the transformer 6 induces a voltage in the secondary winding 8 55 which latter is tuned to resonance with a desired signal by means of the condenser 9.

60 By shunting a part of the secondary winding 8 with the capacity 10 and resistance 11, a load which is controllable in phase and amount is transferred by the close coupling to the electron discharge device 3. By correctly apportioning the number of turns of the secondary which are shunted, the capacity 65 and the resistance, it is possible to maintain

a coupling between the windings of the transformer 6, which at all frequencies in the broadcast range will give a maximum amplification without regenerative distortion or oscillation. This will be clear from Figures 70 3 and 4 wherein,

$i_p R_p$ represents the internal drop of the electron discharge device 3,

$i_p R_1$ is the external resistance drop,

$i_p X_1$ is the external reactance drop,

75 $e_p = -i_p Z_1$ = the A. C. voltage on the plate 4,

e_{g2} is the voltage induced in the secondary winding of the transformer 6 when the primary and secondary of said transformer are wound in the same direction,

80 e'_{g2} is the voltage induced in the secondary winding of the transformer 6 when the windings of the latter are wound in opposite directions,

85 CB is the component of the plate voltage in phase with the grid voltage, and

CA is the component of the plate voltage which must be in phase with the grid voltage before the tube 3 will oscillate.

90 From an inspection of Fig. 3 it will be seen that as the load introduced by the capacity 10 and the resistance 11 is increased, the voltage e_{g2} induced in the secondary winding 8 is of such a phase that the plate voltage e_p is not materially affected by the capacity effect resulting from the close coupling between the primary and secondary windings of the transformer 6. The vector representing the plate voltage e_p is parallel to the vector

95 $i_p Z_1$ representing the external impedance. As the latter is decreased or as the external resistance drop $i_p R_1$ is decreased (see Fig. 4), it will be apparent that the plate voltage e_p approaches more nearly to the phase of the voltage e_{g2} induced in the secondary winding, and the component of the plate voltage tending to produce oscillation increases. As the 100 load is increased the phase angle between the plate voltage and the voltage induced in the secondary winding increases, and simultaneously the dynamic characteristic loop assumes an elongated form which greatly improves the exactness of reproduction, or tends to eliminate distortion. Moreover, increase 105 of the load introduced by capacity 10 and resistance 11 materially increases the breadth of the peak of the resonance curve without affecting the broadness of tuning. This results in equal amplification of the entire side bands, along with the carrier wave, thereby 110 greatly improving the quality of reproduction.

115 In Fig. 2 there is illustrated another form of the present invention wherein the primary of a transformer 21 is formed in two parallelly connected sections 20^a and 20^b and the battery 7 is connected to said primary winding intermediate the sections, as at a point 22, and the outer ends of the two sections of the primary winding are connected together at a 120

125 130

point 23 in the lead to the plate 4 of the electron discharge device 3. The secondary winding of the transformer 21 is also formed in two parallelly connected sections 24^a and 24^b and the filament 18 of a second electron discharge device 19 is connected to the secondary winding intermediate the sections 24^a and 24^b, as by means of a suitable conductor 25. In shunt with a suitable number of turns 10 of each of the sections 24^a and 24^b, which are in close coupling with the sections of the primary winding, is a conductor 26 which is connected in series with a condenser 10 and a resistance 11, which latter is connected at a 15 suitable point 27 to the conductor 25. A tuning condenser 9 is preferably in parallel with the sections of the secondary winding, and the opposite ends of the latter are connected at a point 28 to the conductor 29 leading to 20 the grid 17 of the electron discharge device 19.

It will be understood that the number of turns of the secondary to be shunted by the capacity and resistance, the value of the capacity, and of the resistance will vary in accordance with the elements of the circuit, as for example, the internal resistance of the audion or audions employed, etc. However, one example will be given which is capable of 30 producing superior results in an ordinary receiving apparatus:

From the primary winding in two sections, 53 turns in each section, of #36 D. S. C. wire; form the secondary winding in two 35 sections, 80 turns in each section of #36 D. S. C. wire. Connect 40 turns of the secondary, 20 in each of the sections, in series with a .003 mfd. capacity and a 400 ohm resistance. The thickness of the insulation 40 between the primary and secondary coils may be 3/32 of an inch and said coils may be wound in the same direction.

The two sections of each of the primary and secondary are wound on the same axis 45 and in the same sense, but the secondary may be wound in either the same or the opposite sense from the primary. In the form shown in Fig. 2 the battery 7 is connected to the point of junction of the two sections of the 50 primary, the two ends of said sections being connected in the circuit to the plate 4; similarly the filament of the tube 19 is shown as connected to the point of junction to the two sections of the secondary, the two ends 55 of said sections being joined in the lead to the grid 17. It is to be expressly understood, however, that it is within the contemplation of this invention to reverse either or both of these connections, i. e., the lead from the 60 plate 4 may be connected to the point of junction of the two sections of the primary, with the two ends of said sections connected to the battery; and the lead to the grid 17 may be connected with the point of junction of 65 the two sections of the secondary, with the

ends of said sections connected to the filament 18. While the shunted capacity and resistance have been shown as applied only in the secondary circuit, advantageous results can be obtained by applying the shunted capacity and resistance in the primary circuit either with or without shunted capacity and resistance in the secondary and whether the primary and secondary are formed in one or more sections. It is also to be expressly 70 understood that where the primary and secondary are formed in sections, said sections may not be equal, the number of turns in the two sections of the primary may be different or the turns in the two sections of the secondary may be different or the number of the turns in both the primary and the secondary may be different. While the closely coupled sections of the primary and secondary have been shown as adjacent the point of junction 75 of the sections of the primary and secondary, the closely coupled sections could equally well be adjacent the opposite ends of the sections of the secondary, or the section of the secondary which is not closely coupled with 80 the primary can be more or less removed from the closely coupled section of the secondary, or placed in non-inductive relation therewith and suitably connected in series with the closely coupled section. While as 85 above pointed out it is preferred to wind the two sections of the primary and the two sections of the secondary in the same sense, either or both of the primary and secondary could have their sections wound in the opposite sense by connecting the corresponding 90 ends of the reversely wound sections. The extent to which the sections of the primary and the sections of the secondary may be separated from each other may also be varied. 95

It is therefore to be expressly understood that the specific arrangement illustrated on the drawings and the specific example of a construction of a transformer above given are only by way of illustration and not to be 100 taken as in any way defining the limits or uses of this invention.

The present invention is particularly adapted for use in combination with the radio frequency amplifier tubes used in receiving sets. The device may be used in combination with any desired number of such tubes, with any suitable detecting means and audio-amplifying means. Reference will 110 therefore be had to the appended claims for 115 a definition of the limits of the invention.

What is claimed is:

1. In combination with a plurality of vacuum tubes comprising grid, filament and plate electrodes, means including closely coupled primary and secondary windings for connecting said tubes in cascade, and means in shunt to a portion only of said secondary winding for preventing oscillation of one or 120

more of said tubes due to the coupling between said windings.

2. In a vacuum tube amplifier system comprising two or more tubes in cascade, coupling means for said tubes including primary winding, a secondary winding, a portion of said secondary being closely coupled to the primary, means for tuning said secondary winding, and means for maintaining the current induced in the closely coupled portion of the secondary at a phase different from the inducing voltage, the total inductive and capacitative reactance of the secondary winding being maintained at resonance value through the range of broadcasting frequencies.

3. In an amplifier system the combination of a vacuum tube having an output circuit, a second circuit, and means for coupling said output and second circuits, said means comprising primary and secondary windings, and means in shunt to a portion only of said secondary winding for maintaining the voltage induced therein at a different phase from that of the inducing current.

4. In an amplifier system the combination of a vacuum tube having an output circuit, a second circuit, and means for coupling said output and second circuits, said means comprising primary and secondary windings, and means for controlling the feed back to said vacuum tube including a capacity and a resistance in series, said last named means being in shunt to a portion only of said secondary.

5. In an amplifier system, the combination of an audion having an output circuit, a second circuit, and means for inductively coupling said circuits including primary and secondary windings, and means including capacity and in shunt with a portion only of said secondary for securing large amplification over the broadcast range and for preventing oscillation of said audion.

6. Radio receiving apparatus comprising a plurality of electron discharge devices, a transformer operatively connected to two of said devices, means for tuning the secondary of said transformer, and a capacity and a resistance in series one with the other and in shunt with a portion only of the windings of said secondary.

7. An amplifier system comprising an electron discharge device having an output circuit, an input circuit, a transformer connecting said circuits, one portion of the secondary of the transformer being closely coupled to the primary thereof, and means in shunt with the closely coupled portion of said secondary for controlling the feed-back to said device.

8. A circuit of the class described comprising an amplifier having an output circuit, means including an input circuit, a transformer connecting said input and output circuits, a plurality of series impedances in

shunt with a portion only of the secondary of said transformer, and means for resonating the transformer to a desired signal frequency.

9. A device for operatively connecting 70 radio frequency amplifier tubes comprising a primary winding, a secondary winding inductively associated with said primary winding, one portion of the secondary winding being closely coupled with the primary winding, 75 and impedances in shunt to said closely coupled portion only for changing the phase of the voltage induced in said secondary winding.

10. An amplifier system comprising an 80 electron discharge device having output electrodes, a sectional winding connected to said electrodes, a secondary winding inductively associated with said first named winding, said secondary being formed in sections, 85 means for completing an electrical circuit connected to said secondary winding, and a series capacity and resistance in shunt to a portion of each of the sections of said secondary winding.

11. Radio receiving apparatus comprising a plurality of electron discharge devices, a transformer operatively connected to two of said devices, means for tuning the secondary of said transformer, and means in shunt with 95 a portion only of said secondary for preventing oscillation.

12. An amplifier system comprising an electron discharge device having output electrodes, a sectional primary winding connected to said electrodes, a sectional secondary winding inductively associated with said primary winding, means for completing an electrical circuit connected to said secondary winding, and means in shunt to a portion only 100 of said secondary for preventing oscillation of said device.

13. An amplifier circuit comprising an electron discharge device having output electrodes, a primary winding connected to said electrodes, means including a secondary winding inductively and closely associated with a portion only of said primary winding, and means in shunt to said secondary winding for maintaining the current induced in the secondary at a different phase from that of the inducing voltage.

14. An amplifier system comprising an electron discharge device having output electrodes, a sectional winding connected to said electrodes, a secondary winding inductively associated with said first named winding, said secondary being formed in sections, means for completing an electrical circuit connected to said secondary winding, and series impedances in shunt with a portion of said secondary winding.

15. An amplifier system comprising an electron discharge device having an output circuit, an input circuit, a transformer con-

necting said circuits, one portion of the secondary of the transformer being closely coupled to the primary thereof, and a capacity and a resistance in shunt with the closely coupled portion only of said secondary for controlling the feed-back to said electron discharge device.

16. An amplifier system comprising an electron discharge device having output electrodes, a primary winding connected to said electrodes, a secondary winding inductively associated with said primary, and means in shunt to a portion only of one of said windings for preventing oscillation of said discharge device.

17. An amplifier system comprising an electron discharge device having output electrodes, a primary winding connected to said electrodes, said winding having sections connected in parallel, a secondary winding formed in sections inductively associated with said primary winding, and loading means in shunt with a portion only of one of said windings.

18. An amplifier system comprising an electron discharge device having output electrodes, a primary winding connected to said electrodes, a secondary winding inductively associated with said primary, one of said windings being formed in sections with the sections connected in parallel, and loading means in shunt to a selected portion only of one of said windings.

19. An amplifier system comprising an electron discharge device having output electrodes, a primary winding having parallelly connected sections, the center of said winding being connected to one of said electrodes and the ends of said winding being connected to the other of said electrodes, a sectional secondary winding associated with said primary winding, the sections of the secondary being parallelly connected, and loading means connected to said secondary winding.

20. In an amplifier system, the combination of a thermionic tube having an aperiodic output circuit, a second thermionic tube having a tuned input circuit a portion of which is inductively coupled to said output circuit, and means for detuning the coupled portion of the input circuit whereby the voltage across said portion is out of phase with the current traversing the same.

21. In an amplifier system, the combination of a thermionic tube having an aperiodic output circuit, a second thermionic tube having a tuned input circuit a portion of which is inductively coupled to said output circuit, and means for putting the consequent capacitative coupling of said circuits into an interphase relation with the inductive coupling.

In testimony whereof we have signed this specification.
